UNITED STATES PATENT OFFICE.

ARCHIBALD McCALLUM, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,792, dated April 16, 1872.

Specification describing a new and original Design for a Carpet, invented by ARCHIBALD McCALLUM, of Halifax, in the county of York, England.

The accompanying photograph fully illustrates my new design.

This invention relates to a new ingenious carpet design, made in imitation of two kinds of narrow strips, which are laid at right angles alternately over and under each other, a succession of two kinds of rectangular figures be-

coming thereby visible, as shown. The two figures are severally ornamented by borders and inner decorations, as shown.

I claim as my invention—

The design for a carpet, composed of the two kinds of figures, as shown.
